(57) **CLAIM**

The ornamental design for a car cover, as shown and described.

DESCRIPTION

FIG. 1 is a top front perspective view of a car cover, showing my new design;

FIG. 2 is a top plan view thereof, the bottom plan view being a mirror image thereof;

FIG. 3 is a right-side elevation view thereof, the left-side elevation view being a mirror image thereof; and,

FIG. 4 is a front elevation view thereof, the rear elevation view being a mirror image thereof.

The car cover is shown with symbolic breaks in its length and width. The appearance of any portion of the car cover between the break lines forms no part of the claimed design.
